CLAIM

We claim the ornamental design for a hair clipper housing, as
shown and described.

DESCRIPTION

FIG. 1 is a perspective view of a hair clipper housing.
FIG. 2 is a top view of the design shown in FIG. 1.
FIG. 3 is a bottom view of the design shown in FIG. 1.
FIG. 4 is a right view of the design shown in FIG. 1.
FIG. 5 is a left view of the design shown in FIG. 1.
FIG. 6 is a left view of the design shown in FIG. 1, with a
portion of the unclaimed environment removed for illustrative
purposes.
FIG. 7 is a front view of the design shown in FIG. 1; and,
FIG. 8 is a rear view of the design shown in FIG. 1.
The broken lines shown in the drawings illustrate the envi-
ronment of the article and form no part of the claimed design.
